DISCHARGE TUBE

Minne Kuipers, Eindhoven, Netherlands; vested
in the Alien Property CustodianApplication May 29, 1941, Serial No. 395,888
In the Netherlands June 25, 1940

6 Claims. (Cl. 250—27.5)

The present invention relates to discharge tubes and to a method of manufacturing the same. More particularly, the invention relates to vapour filled discharge tubes, for example mercury vapour discharge tubes with incandescent cathodes, which filling is replenished from a supply of vapour producing substance provided in the foot of the tube.

It is known to provide in such discharge tubes a vapour-producing supply in the foot of the tube, preferably in a supply vessel specially provided for this purpose for in most cases it is possible to construct the tube in such manner that the lower part of the foot constitutes the coldest point of the discharge vessel and the required low pressure can be thus maintained.

It sometimes entails great drawbacks when the vapour-producing material, for example the liquid mercury, is free to move within the tube and comes into contact with the electrodes. Especially in incandescent cathode current-converting tubes for high voltages there arises in this case the drawback that undesired emission and discharge phenomena may disturb the operation of the tube; for example due to return discharges, and even may give rise to deterioration of the tube. Such is the case, for example, with a known construction in which the sealed-off end of the exhaust tube, which is provided at the lower end of the discharge vessel and is directed downwards, is utilised as the supply vessel for the mercury. In this case no means are provided for keeping the mercury away from the discharge space proper and, when the tube is being exhausted and filled, it is necessary to provide the mercury temporarily in the discharge vessel before it is possible to seal-off the tube. More particularly after transport of the tube it may occur that the latter has to be "burned out" anew at a reduced voltage before the tube can be loaded at the full allowable voltage. There are even cases wherein it is no longer possible to restore the initial blocking capacity of the tube when only once mercury has deposited, for example on the surface of the anode.

It is already known to provide the mercury in such a case in a supply vessel which communicates with the discharge space proper by means of a narrowed portion, for example a capillary tube. Apart from the fact that this construction may give rise to mechanical inconveniences, especially as regards the risk of cracking of the capillary tube, there arises in this case the necessity of taking particular measures during manufacture for providing the vapour-producing sub-

stance in the supply vessel, especially if the requirement is made that this material should be kept remote from the discharge space proper.

The invention has for its purpose to construct and to arrange the supply vessel in such manner that the vapour-producing supply may be introduced in a very simple manner without reaching the discharge space and that in this case neither during transport nor during operation of the tube does an excess of vapour-producing substance penetrate into the discharge space.

According to the invention, the supply vessel for the vapour-producing substance arranged in the foot of the tube may be provided at the side of and preferably concentrically around the exhaust tube and communicates with the latter in such manner that during exhaustion the vapour-producing substance may be introduced into the supply vessel from that end of the exhaust tube which is remote from the discharge tube without the substance being able to penetrate into that end of the tube which leads to the discharge space whilst the latter end and the supply space are connected to the other end of the exhaust tube through paths of low resistance to the circulation of gases or vapours.

This form of construction has the advantage that the supply vessel comes to lie, as it were, in a side-branch of the exhaust tube so that the vapour-producing substance can reach the supply vessel from a supply connected to the exhausting installation without penetrating into the discharge space, whilst it is very simple to prevent vapour-producing material from distilling over to the discharge space by maintaining the temperature of the supply vessel and the lower exhaust tube below that of the discharge vessel and the upper exhaust tube.

It is advantageous to cut through the exhaust tube provided in the foot of the discharge tube for the reception of the supply vessel and to cause the tube portions which come into communication with the discharge space and with the exhausting device respectively, to protrude in alignment with one another at the upper end and at the lower end into the supply vessel and to extend up to the immediate vicinity of one another so that the interior space of the exhaust tube, which neither alters its direction nor is narrowed in any way at this point, only communicates with the supply space through an annular slit having a height of 3 mm. at the most. This construction affords the advantage that the exhausting conduit remains free from obstacles which might retard the exhaustion

process whilst the possibility that liquid vapour-producing material may penetrate during transport, for example due to the tube being turned upside down or due to shocks, into the exhaust tube and through the latter into the discharge space is substantially eliminated owing to the fact that the opposite ends of the exhaust tube mutually screen one another so that the possibility that a drop of mercury may penetrate through the narrow annular slit into the exhaust tube is extremely small.

This construction may further be improved by closing those ends of the two portions of the exhaust tube which are turned towards one another by means of fine metallic gauze having a mesh width of 0.2 mm. at the most, for example of nickel wire and preferably in the shape of caps. If with this construction a drop of the vapour-producing material might reach the space between the pieces of gauze the latter still prevent in an efficient manner the material from penetrating into both portions of the exhaust tube. These caps of gauze do not give rise to an inadmissible circulation resistance for the gases or vapours pumped away or for the vapours passing from the vapour-producing supply to the discharge space.

The invention will be explained more fully with reference to the accompanying drawing which represents, by way of example, two embodiments thereof.

Fig. 1 represents an incandescent cathode rectifying tube provided with a supply vessel according to the invention.

Fig. 2 shows one favourable form of construction of the supply vessel.

Fig. 1 represents a rectifying tube comprising a cylindrical glass vessel 1, a directly heated incandescent cathode 2, and an anode 3. At one of the ends of the vessel 1 supply conductors 4 of the cathode are sealed into a pinch 5 and at the other end a supply conductor 6 of the anode is sealed into the glass wall by means of a chrome-iron plate 7. The cathode helix 2, which is directly heated and is provided with an activating layer of oxide, is surrounded by a cylindrical screen 8 which is conductively connected to one of the cathode poles and is constructed so as to be closed at the back-side of the cathode and open at the end turned towards the anode. On the circumference of the screen 8 there is a flat screening ring 9 which serves to prevent the passage of a discharge between the anode 3 and those parts of the space behind the cathode which have cathode potential. According to directions the maximum temperature of the supply of liquid mercury within the tube amounts to 50° C., which corresponds to a mercury vapour pressure of $12.5 \cdot 10^{-3}$ mms. of mercury. The anode 3 is constituted by a cylinder open at one end. Said cylinder has been drawn from a sheet of nickel and blackened by carbonisation or in any other manner and surrounds the open end of the cathode screen in the way of a cup. Within the stem tube 11 there is a glass tube 12 which acts during manufacture as the exhaust tube and in which is incorporated the supply vessel 13 for liquid mercury 14. According to the requirements set by the ambient temperature or by the manner of arrangement of the tube, the temperature of this supply, which determines the vapour pressure of the tube, may be regulated during manufacture once for all by arranging the vessel in the exhaust tube at a higher or lower level. During exhaustion the

mercury may be introduced from below through the exhaust tube and over the lengthening piece 15 of the latter into the supply vessel 13 without attaining the discharge space proper. That portion 15 of the glass tube 12 which leads to the interior of the discharge tube protrudes by an extension 16 into the supply vessel 13 and thus forms, jointly with the extension 15, a mercury trap which serves to prevent, in cooperation with the extension 15, the passage of liquid mercury to the discharge space during transport of the tube. The extensions 15 and 16 are covered by sheets of nickel gauze 17 and 18 respectively having a mesh width of 0.135 mm. and a wire diameter of 0.045 mm., which prevents spattering mercury when attaining the slit with a height of about 2 mms. between the extensions, from penetrating into the exhaust tube. The rectilinear shape of the latter tube is not altered by the above-described construction and the gauze does not constitute an appreciable obstacle to the passage of gases to be pumped away to the exhausting device or of the liquid mercury, during the filling operation, in the direction of the supply vessel 13. In the last-mentioned case it is even advantageous that the ascending mercury is divided and slightly braked by the gauze. The construction described renders it superfluous to burn out the tube anew when it is put into operation, for example after transport, for the purpose of removing excessive mercury which sticks to the electrode and is favourable to the production of back-ignition.

The tube, which is represented to scale in the drawing, has a bulb diameter of 60 mms. and the annexed scale permits to determine the other dimensions of the tube in any easy manner. The incandescent cathode has a heating voltage of 5 volts and a heating current of 14 amperes. The maximum mean value of the anode current which is allowable during operation amounts to 2.5 amps., the peak value being about 10 amps. According to regulations the tube can sustain in the blocking phase a maximum peak value of the voltage of 20,000 volts and for a short time this value may even amount to 45,000 volts. There exists reason to assume that this high load capacity is due not only to the particular construction of the complex of discharge vessel, cathode, cathode screen and anode but also to the fact that for the liquid mercury use is made of a supply vessel according to the invention. It has been found that in some cases tubes not provided with a supply vessel according to the invention but for the rest constructed as shown in the figure could sustain in less high blocking voltages whilst with tubes according to the invention when submitted to tests of long duration it could be ascertained that even after a comparatively long period of operation the discharge space proper had remained in a remarkable manner free even from traces of liquid mercury.

With the form of construction represented to scale in Fig. 2 constituent parts corresponding to those of the supply vessel according to Fig. 1 are denoted by the same reference numerals whilst also in this case the dimensions may be determined by means of the annexed scale. In this case the lengthening piece 15 has a funnel-shaped extension 20 which terminates about at the height of the lower end of the lengthening piece 16, a cap 21 of metal gauge being provided which takes up the lengthening piece 16 in a pointed re-entrant portion 22, the arrangement being such that liquid mercury coming

from below is diverted by the point 22 of the tube 12-16 and can easily attain the supply space through the funnel-shaped extension 20 and the gauge 21. The peculiarity of the construction is that it is impossible for the mercury in the vessel 13 when moving towards the discharge space to attain the tube 12-16 whilst it does not cause any inconvenience if in the case of an opposite shock the mercury might come again through the cap 21 and the funnel-shaped portion 20 into the tube 15. In this case, with a renewed reversal of the movement, it is diverted again by the point 22 and falls back into the supply vessel. The dimensions of the construction must be so chosen that no excessive speed is imparted to the mercury, which may be achieved by maintaining the lengths of the free paths in the supply vessel as small as possible; preferably they should not be longer than double the diameter of the exhaust tube. This remark more particularly applies to the diameter and the length of the supply vessel and as well to the construction of Fig. 1 as to that according to Fig. 2. These dimensions should, however, not be taken so small that due to capillarity the mercury may stick between the gauge and the neighbouring walls. Besides, it is advisable not to take an excessively large quantity of mercury since thus the possibility of penetration through the gauge is enhanced, *inter alia* owing to the enlarged surface of contact between mercury and gauge and to the increase of the moving mass of mercury.

What I claim is:

1. A discharge tube comprising an envelope, electrodes and a vapor filling within the envelope, an exhausting member connected to the envelope, said member comprising a chamber portion and two tubular portions extending into said chamber, one of said tubular portions forming a path of low resistance to vapors between the space within the envelope and the space within the chamber, the second tubular portion serving to introduce a vapor-producing material into said chamber, and a supply of the vapor-producing material within said chamber at one side of one of said extending portions.

2. A discharge tube comprising an envelope, electrodes and a vapor filling within the envelope, an exhausting member connected to the envelope, said member comprising a chamber portion and two tubular portions arranged in alignment and extending into said chamber, said tubular portions forming a space with said chamber portion and having their adjacent ends spaced apart to form an annular slit, a supply of vapor-producing material within said space, one of said tubular portions being connected to the space within the envelope, and the other tubular portion serving to introduce the vapor-producing material into the space formed in said chamber.

3. A discharge tube comprising an envelope, electrodes and a vapor filling within the envelope, an exhausting member connected to the envelope, said member comprising a chamber portion and two tubular portions arranged in

alignment and extending into said chamber, said tubular portions forming a space with said chamber portion and having their adjacent ends spaced apart to form an annular slit having a height of 3 mms. at the most, a supply of vapor-producing material within said space, one of said tubular portions being connected to the space within the envelope, and the other tubular portion serving to introduce the vapor-producing material into the space formed in said chamber.

4. A discharge tube comprising an envelope, electrodes and a vapor filling within the envelope, an exhausting member connected to the envelope, said member comprising a chamber portion and two tubular portions arranged in alignment and extending into said chamber, said tubular portions forming a space with said chamber and having their adjacent ends spaced apart, metallic gauze screen members disposed over said adjacent ends, a supply of vapor-producing material within the space formed in said chamber, one of said tubular portions being connected to the space within the envelope, and the other tubular portion serving to introduce the vapor-producing material into the space formed in said chamber.

5. A discharge tube comprising an envelope, electrodes and a vapor filling within the envelope, an exhausting member connected to the envelope, said member comprising a chamber portion and two tubular portions arranged in alignment and extending into said chamber, said tubular portions forming a space with said chamber portion and having their adjacent ends spaced apart to form an annular slit, said chamber having an internal length and diameter less than twice the diameter of the tubular portions, a supply of vapor-producing material within the space formed in said chamber, one of the tubular portions being connected to the space within the envelope, and the other tubular portion serving to introduce the vapor-producing material into the space formed in said chamber.

6. A discharge tube comprising an envelope, electrodes and a vapor filling within the envelope, an exhausting member connected to the envelope, said member comprising a chamber portion and two tubular portions arranged in alignment and extending into said chamber, one of the tubular portions being connected to the space within the envelope, a substantially conical metallic gauze screen disposed over the extending end of said tubular portion, the second tubular portion having its end extending into the chamber forming a divergent opening surrounding said conical screen, and a substantially conical metallic gauze screen extending from the divergent opening of said second tubular portion and surrounding said first conical screen, said second tubular portion serving to introduce a vapor-producing material into said chamber, and a supply of the vapor-producing material within said chamber at one side of one of said extending portions.
